(57) **CLAIM**

The ornamental design for an electric water gun as shown and described.

DESCRIPTION

FIG. 1 is a perspective view of an electric water gun showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a partial enlarged view of portion 9 in FIG. 1;

FIG. 10 is a partial enlarged view of portion 10 in FIG. 2; and,

FIG. 11 is a partial enlarged view of portion 11 in FIG. 2. The broken lines depict portions of the electric water gun and form no part of the claimed design.

The dot dash line is included for the purpose of illustrating the bounds of the enlarged view and forms no part of the claimed design.
